G. A. STRUB

TIE PRESS

Filed May 12, 1927

Inventor

Gustav A. Strub.

By *Fancet F. Dauphelin*

Attorney

UNITED STATES PATENT OFFICE.

GUSTAV A. STRUB, OF TOLEDO, OHIO.

TIE PRESS.

Application filed May 12, 1927. Serial No. 190,715.

My invention has for its object to provide an efficient press for ties, belts, and other articles of any nature that are formed of sheet material and which may be smoothed out by a constant pressure being applied thereto. The invention is particularly applicable to fabric material, such as silk and cotton goods, and it is used with advantage for pressing and smoothing out ties and 10 cloth belts.

The invention provides a means whereby neckties or similar wearing apparel may be readily placed in position and subjected to pressure. Preferably the articles are subjected to a smoothing pressure for a considerable period of time and so that, when they are removed from the device, they are invariably smoothed out and pressed to the desired shape.

20 The invention may be contained in pressing devices of different forms, and to illustrate a practical application of the invention, I have selected a pressing device that contains my invention, as an example of the 25 different structures that embody the invention, and shall describe the device selected for purposes of illustration hereinafter. The device referred to is shown in the accompanying drawing.

30 Fig. 1 of the drawing is a front view of a tie-press which embodies my invention. Fig. 2 is a view of a section taken on the plane of the line 2—2 indicated in Fig. 1. Fig. 3 is a view of a section taken on the 35 plane of the line 3—3 indicated in Fig. 1. Fig. 4 is a view of a section taken on the plane of the line 4—4 indicated in Fig. 1.

The tie-press illustrated in the figures is provided with a base 1 which may be secured 40 to a suitable support or to a wall by means of screws which may be located in the holes 2 formed in the upper ends of the base 1. The central portion of the base 1 is raised as at 3 and also at its ends as at 4.

45 The central portion 3 is provided with bosses 5 in which springs 6 may be located and a presser plate 10 may be supported on the base 1 by means of the screws 11 which extend through the plate and are threaded 50 into the tapped holes formed in the bosses 12. Also the plate 10 is provided with flanges 13 at its upper and lower ends that overlap surfaces formed at the ends of the raised portion 3 of the base 1. The flanges

13 are adapted to telescope or slide over the 55 said surfaces. Also the presser plate 10 is provided with flanges 14 that fit between the flanges 15. The flanges 14 and 15 extend along the side edges of the presser plate 10 and the base 1.

The springs 6 located in the bosses 5 press 60 against the inner surface of the presser plate 10 and the heads of the screws 11 limit the outward movement of the presser plate 10 under the influence of the springs 6. The 65 presser plate 10 which is thus elastically held in position may be yieldingly pressed towards the base 1 against the pressure of the springs 6. Preferably four springs 6 are located intermediate the base 1 and the presser plate 70 10 in order to yieldingly press the presser plate from the base 1 at four points near the corner of the presser plate.

The base 1 is also provided with a pair of ears 18 to which may be hingedly connected 75 a second presser plate 19. The presser plate 19 is preferably so shaped as to substantially cover the presser plate 10. The base 1 is also provided with a spring latch 20 that may be, if desired, hingedly connected to the 80 base 1 by means of pintles 21 and a plate 22 is hingedly connected to the latch 20. The plate 22 is secured to the back of the base 1 by means of a screw 23. The latch 20 is provided with a spring end 24 that 85 may be slipped over the beaded or flanged edge 25 of the presser plate 19 which forms a cover to the pressing device. The length of the latch 20 and the length of the lugs 18 are such that the presser plate or cover 90 19 will be located in contact with the presser plate 10 when it is moved substantially to its outermost position with reference to the springs 6 and the screws 11.

The ridges 4 located at the upper and 95 lower ends of the base 1 are each provided with a spring 28 that extends substantially the length of its associated ridge. Each spring 28 has an end portion 29 that may be bent over one end of the ridge 4 and secured by means of the screw 30. The other end of each spring is turned out from the ridge so as to form the lip 31. When it is desired to insert any wearing apparel, such as a belt or tie, that it is desired to smooth 100 out or to press into any desired fold, all that is required is to open the cover 19 by pushing the latch 20 from the beaded edge 105

25 of the presser or cover plate 19, where-
upon the plate 19 may be swung upon its
hinges. The tie or belt or other article of
apparel may be then slipped under the
5 springs 28 and placed upon the surface of
the presser plate 10 in the desired position
to smooth the tie or belt or other apparel.
The presser plate or cover 19 is then closed
and secured in the closed position by means
10 of the latch 20. The springs 6 will then
cause the presser plate 10 to press the ap-
parel against the surface of the cover 19.
The two opposed surfaces of the presser
plates 10 and 19 are preferably made smooth
15 so that, by the constant pressure produced
by the springs 6 for a period of time, the
material located between the plates will be
smoothed out. A number of ties or other
apparel of suitable size may be placed in
20 between the two plates so that quite a num-

ber may be smoothed and pressed out by
the pressure exerted between the two plates
10 and 19.

I claim:

In a press for apparel, a base, a presser 25
plate, the presser plate having flanges over-
lapping parts of the base for guiding the
presser plate relative to the base springs
located intermediate the presser plate and
the base, a second presser plate hingedly 30
connected to the base, the first named
presser plate being located between the sec-
ond named presser plate and the base, means
for securing the second named presser plate
in position against the pressure of the said 35
springs, and clips located at the upper and
lower ends of the base.

In witness whereof I have hereunto signed
my name to this specification.

GUSTAV A. STRUB.
